ANNA K. FRASIER, OF LEAVENWORTH, KANSAS

DARNING LAST

Application filed June 26, 1930. Serial No. 464,026.

This invention relates to a darning last of the type used when darning stockings and one object of the invention is to provide a last of such formation that when it is placed within a stocking and particularly in the toe portion of the stocking, it will not cause the stocking to be distorted by stretching and not fit properly upon a person's foot when worn.

Another object of the invention is to provide a darning last which can be very easily inserted into a stocking and conveniently held while the stocking is being darned.

Another object of the invention is to provide a darning last which is simple in its construction and may be formed with a very smooth and polished surface.

The invention is illustrated in the accompanying drawing, wherein:

Figure 1 is a perspective view of the improved last.

Figure 2 is a longitudinal sectional view through the last, with a portion of the handle shown in elevation.

Figure 3 is a transverse sectional view taken through the last on the line 3-3 of Figure 2.

Figure 4 is a longitudinal sectional view through a modified form of last.

Figure 5 is a longitudinal sectional view through another modified form of last.

The improved last constituting the subject matter of this invention consists of a body 1 and a handle 2. The body 1 may be formed of wood having a smooth and polished surface or it may be formed of porcelain, glass, or any other suitable composition. If the body is formed of glass or porcelain, it may be molded as a solid mass or a core 3 of the desired shape, may first be formed of wood or light metal such as aluminum and this core 3 coated with the glass or porcelain, as shown at 4. It will be understood that the body may be formed of solid aluminum or other light metal if so desired or may be formed as a metal shell of the desired shape. The handle is preferably formed separate from the body portion of the last and is provided with a tapered forward end portion 5 which fits tightly into a similarly tapered socket 6 formed in the rear end of the body and is

firmly held therein by a wedging action which takes place when the handle is forced into the socket but the handle may be formed integral with the body, as shown at 2' in Figure 5. 55

The body portion or last proper is of greater width than thickness, as shown in Figure 1, and this body has rounded rear corners 7 at opposite sides of the handle. It should also be noted that the body gradually 60 reduces in width toward its forward end and has transversely curved upper and lower faces 8 and 9 merging into rounded side edge faces 10. Therefore, the last is substantially elliptical in cross section, as shown in Figure 65 3. The front end 11 of the body is rounded or arcuate both transversely and longitudinally of the body and merges into the side edge portions and upper and lower faces thereof. It will thus be seen that there are 70 no sharp corners to prevent a stocking from fitting smoothly against the last. From an inspection of Figures 2, 4 and 5, it will be seen that the body portion of the last is curved 75 longitudinally so that its forward end curves upwardly and it will also be noted that the body gradually reduces in thickness toward its forward end. By having the last formed as set forth above and clearly shown in Figures 1, 2 and 3, it can be easily slipped into 80 the foot portion of a stocking and when it is held by its handle 2 and moved forwardly through the foot of the stocking it will fit properly in the toe portion thereof without stretching or otherwise distorting the foot 85 of the stocking. Therefore, when a darn is made and the last removed the stocking will not have become distorted and, in addition, the darn will have been formed over a last of such construction that it conforms to the 90 shape of the stocking foot and will not bulge. The last may also fit properly in the heel portion of a stocking or any other portion thereof and a neat darn made which will fit smoothly against a person's foot and not 95 form a rough place in the stocking which would make it uncomfortable to wear.

What is claimed is:

A darning last comprising a body tapered transversely toward its front end and having 100

its rear end rounded, the body being of greater width than thickness and having smooth upper and lower faces merging into transversely arcuate side edge faces and said side edge faces merging into the rounded rear 5 end of the body, said body being arcuate longitudinally to curve upwardly toward its front and having its front end arcuate and merging into the side edge faces and upper and lower faces of the body, and a handle 10 secured to the rounded rear end of the body between the upper and lower faces thereof and extending upwardly therefrom in the same general direction as said upper and lower faces.

15 In testimony whereof I affix my signature.
ANNA K. FRASIER. [L. S.]
